UNITED STATES PATENT OFFICE

STEVEN HARDY, OF NEW YORK, N. Y.

CLEANING AND POLISHING FLUID

No Drawing.

Application filed May 24, 1928. Serial No. 280,386.

My invention relates to a cleaning and polishing fluid and it has for an object to provide such a fluid which will effectively remove all dirt from a surface to which it is applied and restore to said surface the finish and polish originally applied to the article when it was new.

The product of this invention is adapted primarily for the cleaning and polishing of high grade woods such for example, as those used in the manufacture of violins and other musical instruments and the more expensive kinds of furniture but it is to be understood that it also may be used for various other purposes.

My cleaning and polishing fluid, consists of a mixture of linseed oil (preferably boiled), olive oil, oil of rosemary, glycerine, oil of cedar, banana oil and spirits of turpentine.

I have found by many experiments that the best results are obtained from the fluid when it comprises the various elements in substantially the following proportions viz:—3 parts linseed oil (preferably boiled), 1 part olive oil, 1 part oil of rosemary, 4 parts glycerine, 2 parts oil of cedar, 1 part banana oil and 12 parts spirits of turpentine, but it is to be understood that slight variations may be made in the proportions without departing from the invention.

These ingredients are thoroughly mixed together in any suitable or preferred manner and when thoroughly mixed, the product is ready for use.

In use, a small amount of the fluid is applied to the surface to be cleaned and polished, either by applying it directly thereto and subsequently rubbing with a soft cloth or by applying it to the cloth and then rubbing the surface with the impregnated cloth. Certain elements of the combination act to remove all grease, dirt etc., from the surface and other elements act to renew the polish on the varnish covering the surface or, if no varnish previously has been applied, to produce a polish on the surface of the wood or other vase to which the fluid is applied. Certain elements also act as a varnish preservative. The excess fluid is then wiped off with

a soft cloth and a clean and polished surface remains.

Having thus described my invention what I claim and desire to secure by Letters Patent of the United States is:—

A cleaning and polishing fluid comprising the following ingredients in substantially the following proportions, 3 parts linseed oil, 1 part olive oil, 1 part oil of rosemary, 4 parts glycerine, 2 parts oil of cedar, 1 part banana oil and 12 parts spirits of turpentine.

In witness whereof, I hereunto subscribe my name.

STEVEN HARDY.
